UNITED STATES PATENT OFFICE

2,660,025

SETTING AND LIKE MECHANISM FOR
TIMEPIECES

Fernand Reymond, Le Sentier, Switzerland

Application June 8, 1951, Serial No. 230,515

Claims priority, application Switzerland
August 21, 1950

6 Claims. (Cl. 58—80)

1

The object of the present invention is a setting mechanism, more particularly, but not exclusively designed for a wristwatch of the automatic winding type.

The said box is characterized by the fact that its back is traversed by the axis of a rotary member having an outer portion and an inner portion and capable of being operated from the outside, on the one hand with the purpose of being able to rotate the whole, on the other hand with the purpose of being able to move it in a direction perpendicular to its axis, in order to bring the inner portion into contact with an element of a movement placed in the case and in order to be able to set the said movement through this agency.

The accompanying drawing shows an embodiment of the object of the invention given by way of example. Fig. 1 is a partial section of the back of the box through the axis of the rotary member; Fig. 2 is a view of the back through the interior; Fig. 3 is a similar partial view.

In the back 1 of the case shown, is made an opening 2 lengthened in the radial direction, which is traversed by the axis of a two-part rotary member, the one outer 3 and the other inner 4, assembled by a screw 5.

The outer part 3 is a disc having a knurled edge 6 and a cannon 7 directed inwardly, in which is threaded the screw 5.

The inner part 4 is a toothed wheel 8, one cannon 9 of which is placed above the cannon 7, the screw 5 maintaining these two parts pressed one against the other and integral one with the other.

The disc 3 carries sealing joints 10, bearing against the back of the case 1 under the effort exerted from the inside by the elastic washer 11, cut out star-shaped.

A reverse arrangement of the joints might be provided by placing them on the inner part, but this solution would be less practical.

It is obvious that due to the lengthened profile of the opening 2 it is possible, in addition to its rotation, to impart to the rotary element formed by the parts 3 and 4, a movement in the direction of the arrows 12, either in the direction of the centre of the case, or in the opposite direction, perpendicularly to the axis formed by the two assembled cannons.

The numeral 13 shows in dot and dash lines the position of a few members of a movement of a watch supposed to be placed in the case described and the numeral 14 shows the position of a

2

toothed wheel integral with the centre pivot and capable of directly driving the train of wheels.

As may be seen from the drawing, by pushing back the rotary member 3 and 4 in the direction of the centre of the case, the inner toothed wheel 4 of the said member is brought into contact with the wheel 14 of the movement, so that by rotating the disc 3, and with it the toothed wheel 4, the setting to time may be carried out.

10 This completed, the rotary member 3 and 4 will be pushed back in the opposite direction, to the starting position shown.

These movements take place parallel to the plane of the back of the case and perpendicularly to the axis of the rotary member.

In order, moreover, to be able to block this member in the two positions of rest and time setting, there is provided a flat annular spring 15, arranged in a corresponding groove in the back of the case, in the manner shown in more detail in Figs. 2 and 3.

As shown in Fig. 2, in which the assembly of the elements forming the axis of the rotary member is indicated in section by 16, the spring 15 is open and terminates in two ends 17 and 18 the profile of which is such that it constitutes both an admission for the axis 16 and may also serve to maintain it in its position of rest, forced back to the outside.

30 By bearing centripetally against the disc 3, the latter is pushed back inwardly and the axis reaches the position of Fig. 3, in which it has separated the ends 17 and 18 of the arms of the spring and is seized between them.

The advantage of this arrangement is to render the movement into the time setting position less easy (entailing a greater effort) than the return to the position of rest, in the direction of which the axis 16, slightly offset, tends to spring by itself.

35 It is understood that the spring 15 does not oppose the rotation of the axis 16.

By reason of the possible direct attack of the train of wheels, in the case of the example described, the time setting mechanism resulting from the use of a watch case according to the present invention allows of momentarily immobilizing the movement, and therefore of time setting by determining at will the corresponding position of the seconds hand.

It is obvious that the rotary member traversing the back of the case might slide in a direction other than radially, and the toothed wheel which it carries, cooperate with a movable member 55 other than a wheel placed in the centre, the main

characteristic of the invention being a case in which the movement of the rotary member in question takes place not axially, but perpendicularly to its axis.

On the other hand, since the inner part of the rotary member could be made to cooperate with any movable member of the movement, it is obvious that the latter forms no part of the invention, although in most cases it will be preferable to adapt it to the case in question, that is to say to provide it with an additional movable member designed to cooperate with the inner part of the rotary member.

What I claim is:

1. A timepiece comprising, in combination, a 15 casing having a first transmission member turnably mounted within same, said casing having a rear wall; a second transmission member located within said casing and being mounted on said rear wall thereof for turning movement and for movement into and out of engagement with said first transmission member; manually engageable means located on said rear wall of said casing on the outside thereof and being operatively connected to said second transmission member for turning the same and moving the same into and out of engagement with said first transmission member; and holding means operatively connected to said second transmission member for releasably holding the same in a first position in engagement with said first transmission member and in a second position out of engagement with said first transmission member.

2. A timepiece comprising, in combination, a casing having a rear wall formed with an elongated opening passing therethrough; a first transmission member located in said casing opposite said elongated opening in said rear wall thereof; a manually engageable member located outside of said casing opposite said opening in said rear wall thereof; elongated connecting means passing through said elongated opening and interconnecting said first transmission member and said manually engageable member, said connecting means being freely movable along the length of said opening and being freely turnable therein; a second transmission member turnably mounted in said casing adjacent one end of said opening to be engaged and turned by said first transmission member when said connecting means is turned and located in a first position adjacent said one end of said opening, and said transmission members being out of engagement with each other when said connecting means is located in a second position distant from said one end of said opening; and holding means operatively connected to said connecting means for releasably holding the same in said positions.

3. A timepiece as defined in claim 2 and wherein in said connecting means comprises an elongated member passing transversely through said elongated opening and wherein said holding means comprises a springy substantially U-shaped

member having a pair of opposite free ends resiliently engaging opposite sides of said elongated member when said connecting means is in said first position and located against one side of said elongated member when said connecting means is in said second position.

4. A timepiece as defined in claim 3 and wherein in said elongated member is cylindrical and said free ends of said U-shaped member are located apart from each other, when said U-shaped member is unstressed, by a distance less than the diameter of said elongated member.

5. A timepiece as defined in claim 4 and wherein in said rear wall of said casing is formed on the inner face thereof with a substantially circular recess in which said U-shaped member is located.

6. A timepiece comprising, in combination, a casing having a rear wall formed with an elongated opening passing therethrough; a first transmission member located in said casing opposite said elongated opening in said rear wall thereof; a manually engageable member located outside of said casing opposite said opening in said rear wall thereof; elongated connecting means passing through said elongated opening and interconnecting said first transmission member and said manually engageable member, said connecting means being freely movable along the length of said opening and being freely turnable therein; and a second transmission member turnably mounted in said casing adjacent one end of said opening to be engaged and turned by said first transmission member when said connecting means is turned and located in a first position adjacent said one end of said opening, and said transmission members being out of engagement with each other when said connecting means is located in a second position distant from said one end of said opening, said connecting means being in the form of a pair of elongated members respectively extending from said first transmission member and said manually engageable member with one of said elongated members located within the other of said elongated members.
